UNITED STATES PATENT OFFICE.

JOHN CHRISTENSON, OF NORTHPORT, WASHINGTON.

HASP.

No. 898,834.

Specification of Letters Patent. Patented Sept. 15, 1908.

Application filed April 2, 1908. Serial No. 424,769.

To all whom it may concern:

Be it known that I, JOHN CHRISTENSON, a citizen of the United States, residing at Northport, in the county of Stevens and 5 State of Washington, have invented a new and useful Hasp, of which the following is a specification.

This invention relates to improvements in hasps and hooks, such as are fitted to doors, 10 gates, and so forth for securing the same in a closed position.

It is well known that with most devices of this kind now in use, little or no provision is made in the construction to hold the door or 15 gate tight against the casing to prevent rattling.

The present invention aims to remedy this defect in so constructing the hasp that it will at all times maintain the parts to which it is 20 applied in close contact.

Another object of the invention is to render the hasp self-adjusting to compensate for the contraction or expansion of the parts to which it is applied. This construction 25 will be found very advantageous when used on gates, barn doors, or other out-buildings where exposure to the weather causes the parts to swell or warp.

With these and other objects in view, as 30 will more fully hereinafter appear, the invention consists in certain novel features of construction and arrangement of parts, herein-after fully described, illustrated in the accompanying drawings, and particularly 35 pointed out in the appended claims; it being understood that various changes in the form, proportions, size and minor details of the structure may be made without departing from the spirit or sacrificing any of the ad- 40 vantages of the invention.

In the accompanying drawings:—Figure 1 is a side view of the device showing it applied to a door or gate. Fig. 2 is a similar view showing a modification of Fig. 1. Fig. 3 is a 45 still further modification applied to a door or gate. Fig. 4 is another modification.

Similar numerals of reference are employed to indicate corresponding parts throughout the several figures of the drawings.

50 In the form shown in Fig. 1, the hasp proper is formed of engaging and attaching members suitably connected by a spring or the like. The sections are preferably formed of steel rod or other suitable material, and in 55 the construction illustrated in Fig. 1, the engaging member is provided with the usual

hook 1 having a slight overhang 2, adapted to engage a fixed eye or staple 3 secured in a well known way to a door, gate or casing. The shank 4 extends backward and away 60 from the bight in the usual manner, and adjacent its free end is curved outwardly and inwardly to form an eye or loop 5 which is bent at right angles to the shaft 4, and lies in a plane with the bill 1. The attaching member is of the approximate length of the diameter of the engaging member, and is provided with a shank 6 which is adapted to engage the eye 5, and its inner end is bent at right angles, and an eye 7 formed thereon which 70 embraces the shank 4 of the engaging member. The outer end of the attaching member is curved outwardly and inwardly forming an eye or loop 8 for the reception of an eye bolt 9 which secures the hasp to a door, 75 gate or casing. Interposed between the eyes 5 and 7 and encircling the shank 4 of the engaging member is a coiled spring 10, the ends of which abut the inner faces of the eyes and normally tend to force the sections apart in 80 the direction of their length. With this construction it is obvious when the hook is applied to a door or gate, it will purposely be placed at a distance from the eye bolt 3 greater than the distance from its pivotal 85 connection 9 to the bill 1, it being understood that the coiled spring 10 is not compressed. Thus, when it is desired to bring the hook into engagement with the eye bolt 3 the shank 4 is forced in the direction of its length 90 against the action of the spring 10 until the bill enters the eye 3, as shown in Fig. 1. In this position there is a tendency of the device, due to the start of the spring 10, to force the door or gate into contact with the 95 casing, thus at all times insuring a tight fit and thereby prevent rattling.

In the modification shown in Fig. 2, the device is shown applied to a door 11 and casing 12. In this case the engaging member is 100 provided with a hook 1^a and a slight overhang 2^a approximately the same as shown in Fig. 1 and which are adapted to similarly engage an eye bolt 3^a anchored or otherwise secured in the casing 12. The shank 4^a extends in the usual manner back from the bill and shank, and its intermediate section is convoluted forming a spiral spring 10^a and the end terminating in an attaching member having an eye 8^a adapted to embrace the eye 110 bolt 9^a anchored or otherwise secured to the door or gate 11. The function of this con-

struction is similar to that of the hasp already described, the spring section 10^a performing a function similar to the spring 10 of Fig. 1.

- 5 In the construction shown in Fig. 3, a resilient rod, preferably formed of steel or other suitable material is intermediately curved or convoluted, for a portion of its length, to form a spring 10'. The opposite 10 ends of the rod are then inserted in the spring and emerge from the opposed ends thereof, forming engaging and attaching members 4' and 6'. The free end of the engaging member is provided with bill and guide portions 15 1' and 2', similar to that already described and adapted to engage an eye bolt 3'. The other end of the attaching member is provided with an eye 8' adapted to embrace the eye bolt 9' by which the device is pivotally 20 connected to the door 11'. This construction is primarily intended for use with heavy gates or doors used in the open where the parts are more or less subjected to the force 25 of wind.
- 25 The operation of the construction is similar to that already described, with the exception that the longitudinal adjustment of the members is limited to a less extent than the construction already disclosed.
- 30 By reference to Fig. 3 it will be readily seen that an extended pull on the member 4' will result in the compression of the spring 10', and, at the same time, have a tendency 35 to narrow the loop 5' formed on the end of the member 4' and embracing the engaging member 6'. This construction of the loop will cause the latter to grip the attaching member 6' and prevent further compression of the spring, and consequent lengthening of 40 the device.

In the construction illustrated in Fig. 4, the engaging member is provided with the bill 3^b and shank 4^b extending backwardly and terminating in a loop or eye 5^b bent at right angles to the shank. A portion of the 45 shank 6^b adjacent one end of the attaching member is curved outwardly and inwardly forming an eye 8^b and the end brought parallel to the shank 6^b forming a stop for the loop 5^b of the engaging member. The shank 50 of the attaching member is inserted through the loop 5^b and the end terminating in a loop 7^b encircling the shank 4^b of the engaging member. A helical spring 10^b having its ends anchored in the loops 5^b and 7^b encircles the shanks 4^b and 6^b and normally holds the loop 5^b in contact with the free end 9^b of the attaching member as illustrated.

What is claimed is:—

1. A hasp embodying engaging and attaching members having their opposed inner terminals yieldingly held for relative longitudinal movement.
2. A hasp embodying engaging and attaching members and a spring connecting 65 the opposed inner terminals of said members.
3. A hasp having an engaging member with an eye formed on one end thereof, and an attaching member adapted to be inserted in said eye, and having a loop on the end 70 thereof adapted to embrace the engaging member, and a coiled spring held by the engaging member.

In testimony that I claim the foregoing as my own, I have hereto affixed my signature 75 in the presence of two witnesses.

JOHN CHRISTENSON.
